No. 36,469.

Patented August 4, 1903.

UNITED STATES PATENT OFFICE.

SAMUEL GOODMAN, OF NEW HAVEN, CONNECTICUT.

DESIGN FOR A BADGE.

SPECIFICATION forming part of Design No. 36,469, dated August 4, 1903.

Application filed June 29, 1903. Serial No. 163,664. Term of patent 7 years.

To all whom it may concern:

Be it known that I, SAMUEL GOODMAN, a citizen of the United States, residing at New Haven, in the county of New Haven and State of Connecticut, have invented and produced a new, original, and ornamental Design for Badges, of which the following is a specification, reference being had to the accompanying drawing, forming a part thereof, and in which the figure is a plan view showing my design.

What I claim, and desire to secure by Letters Patent, is—

The ornamental design for a badge as shown.

In witness whereof I have hereunto set my hand, at New Haven, in the county of New Haven and State of Connecticut, this 27th day of June, 1903.

SAMUEL GOODMAN.
